UNITED STATES PATENT OFFICE.

JOHN GEORGE NIEDERER, OF EAST RUTHERFORD, NEW JERSEY.

TYPE-WRITING MACHINE.

SPECIFICATION forming part of Letters Patent No. 761,247, dated May 31, 1904.

Application filed February 5, 1902. Serial No. 92,722. (No model.)

To all whom it may concern:

Be it known that I, JOHN GEORGE NIEDERER, of East Rutherford, in the county of Bergen and State of New Jersey, have invented certain new and useful Improvements in Type-Writing Machines; and I do hereby declare the following to be a full, clear, and exact description of the invention, such as will enable others skilled in the art to which it appertains to make and use the same.

My invention relates to an improvement in type-writing machines, and more particularly to that class of machines employing two devices for actuating the type-wheel, one actuating device being moved by one set of key-levers and the other device by the other set of key-levers, the object of this invention being to provide means for absolutely and positively locking one of said devices against movement in either direction while the other is in engagement with one of its key-levers.

A further object is to provide means for preventing the flier from moving past its normal position after a key-lever has been released.

A further object is to provide simple and efficient means for locking the type-wheel after it has been set to print a character corresponding with the key which has been pressed.

With these objects in view my invention consists in the parts and combination of parts as will be more fully explained, and pointed out in the claims.

In the accompanying drawings, Figure 1 is a view in elevation, partly in section, showing my improvements, the flier being in its normal position centrally between the two wheel-movers. Fig. 2 is a similar view, the flier being shown partly in elevation and partly by dotted lines and one wheel-mover positively locked against movement. Fig. 3 is a view in elevation, partly in section, showing the flier and type-wheel support in elevation and one of the wheel-movers in section; and Fig. 4 is a view of the same parts in front elevation. Fig. 5 is a sectional view of a portion of the machine. Fig. 6 is a detail view of the type-wheel lock.

1 represents the frame of the machine, car-

rying the usual set of key-levers 2, and 3 is the post on which the type-wheel 30 is mounted in a manner hereinafter explained. The inner ends of the key-levers are arranged in the form of a V, and the lateral arms 4 of the wheel-movers 5 are similarly arranged and are located in a plane above the inner ends of the key-levers so as to be engaged thereby as the latter are elevated. The inner ends of the several key-levers are curved to form cams, and each lateral arm 4 carries a roller 6, which latter is of a length sufficient to be engaged by the entire set of levers which coöperate with its respective arm 4. Hence when a lever is depressed at its outer end its inner or cam end rises and engages the roller and operates, through the mechanism to be hereinafter described, to rotate the type-wheel sufficiently to bring the character thereon corresponding with the depressed lever into position opposite the hammer, so that the forward stroke of the latter impresses such character upon the paper. It will also be observed that the shorter levers, or those on opposite sides of the center, move the lateral arms 4 the least, while the extent of movement is progressively increased by the levers from the center outward.

The lateral arms 4 are integral with the wheel-movers 5 and project forwardly and inwardly therefrom and operate, as previously explained, to move the wheel-movers rearwardly or in a direction to bring the proper character on the type-wheel in a position immediately in front of the hammer. These wheel-movers are pivotally mounted on the posts 6^a, and each is provided on its inner end with a toothed segment 7, both of which latter are designed to engage a segment 8, mounted on a post 9. This segment 8 normally rests in engagement with both segments 7, so that each of the latter is always when the parts are in a state of rest in a position to actuate segment 8. When, however, one wheel-mover is positively actuated by any one of the key-levers of its series, the other wheel-mover is moved by the combined action of its spring 10 and the segment 8 slightly forward into engagement with a stop 22, adjustably secured to the side of the machine-frame in the horizontal

plane of the wheel-mover, thus locking the latter against further forward movement. The rearward movement of the other wheel-mover by the depression of one of the key-levers of its series rotates the segment 8 in the opposite direction. Secured to the segment 8 or forming an integral part of the latter is segmental disk 21, the top surface of which is flush with the top of the segment 8, while its lower surface is in a plane above the segments 7, thus permitting the latter to pass freely under the disk. The segmental disk 21 is of greater diameter than the segmental toothed wheel 8 and is located diametrically opposite the teeth of said wheel, so that when the teeth of segment 8 are in engagement with the teeth of one of the wheel-movers 5 the disk 21 projects over the inner end of the other wheel-mover 5.

Each wheel-mover 5 is provided on its upper face near its forward edge with an upwardly-projecting pin 11, and when all the parts of the machine are at rest these two pins rest slightly in advance of the front edge of the disk 21, as clearly shown in Fig. 1. If now one of the key-levers (say one engaging the wheel-mover on the left side of Fig. 1) be depressed, the corresponding wheel-mover will be forced rearwardly, as shown in Fig. 2, thus partly rotating the segment 8. This movement of the segment 8 forces the other wheel-mover 5 forwardly against its stop 22, or rather releases the same so that its spring 10 may draw it against its stop, and carries the segmental disk 21 around in a position to engage its pin 11, and thus absolutely lock said wheel-mover, as shown in Fig. 2, against any movement whatsoever. Hence it is apparent that after one key has been struck, all of the key-levers which actuate the other wheel-mover will be locked and so held until the key which actuated the other wheel-mover has been released.

The mechanism thus far described is for locking one set of the levers when any one of the keys of the other set is depressed and to prevent the operation of one wheel-mover when the other is actuated. In addition to this the machine is also provided with a device which positively prevents any interference between the key-levers of the same set, so that after one key-lever has been actuated the others are either locked against movement or have not sufficient throw to engage the lateral arm of the mover, said device also serving to stop the operation of the gearing which actuates the type-wheel when the type-wheel has been turned to present a particular character to writing position. This mechanism comprises a flier 14, rigidly secured to the upper face of segment 8, and spring-abutments 15, carried by the lateral arm 4 of the wheel-movers 5, serve to prevent the movement of the flier and gearing past their normal positions after a key-lever has been re-

leased. The flier 14 normally rests in a central position between the two sets of key-levers, as clearly shown in Fig. 1, and is provided with a downwardly-turned free end 16, which rests normally in a plane above the inner ends of the key-levers when the latter are at rest, but below the plane of the tops of said levers when the rear ends of the latter are raised. Hence if one of the levers of the left-hand set—say the lever representing the letter "Q"—be struck the inner end of this lever engaging the roller on lateral arm 4 forces the wheel-mover rearward, as shown in Fig. 2, thus bringing the rear end of said lever up in the path of the flier 14, which will strike it, and thus effectually lock the parts against further movement. If now any one of the key-levers in the same series be struck, it will be free to move; but as the lateral arm is out of the path of the movement of said lever such movement will have no effect whatever on its wheel-mover. In Fig. 2 I have represented the letter "Q" as the outer lever of the left-hand series. If, however, any one of the levers of the same series be struck—say lever 17 of Fig. 1—such movement will carry the wheel-mover back a predetermined distance and the flier 14 into contact with the lever, thus carrying the lateral arm 4 out of the path of all the levers of the same series to the left of lever 17 and locking all those to the right of lever 17 against movement. The spring-abutments 15 normally rest on opposite sides of a stop 18 on the flier 14. As soon, however, as a key is depressed the movement of the wheel-mover thus actuated by said key carries its abutment 15 out of the path of stop 18 to permit the flier, with its stop thereon, to move until the former comes in contact with the lever which has been actuated. To cause the abutment 15 to thus move out of the path of the flier-stop 18, the space between the first two teeth of the segment 7 of each wheel-mover is made of greater width than the other spaces of said segment, so that when a wheel-mover 5 is first moved by the depression of a key-lever there will be sufficient lost motion or play between the segments 7 and 8 to permit the wheel-mover 5 which has been actuated to move far enough to carry the spring-abutment 15 on said wheel-mover out of the path of the flier-stop 18 before the flier is moved. The other abutment, however, still remains in the path of the stop, and when the key which has been actuated is released the flier swings around to its normal position and the stop thereon being prevented from further movement by coming in contact with the spring-abutment 15, which will bring it to a sudden stop without any shock whatsoever.

The flier 14 carries a toothed segment 19, mounted to rotate within the segmental disk 21 and segment 8, and the toothed segment meshes with and transmits motion to a pinion 130

20. The pinion 20 is provided with a collar 23, mounted to rotate in a bracket 24, secured to the frame of the machine, and to said pinion a star-wheel 25 is secured and adapted to be engaged by a dog 26 to lock the type-wheel when the same has been positioned. A sleeve 27 is mounted loosely on the post 3 and passes freely through the collar 23, pinion 20, and wheel 25 and is movable freely 5 in a vertical direction through these parts, but is made to rotate therewith by means of a spline 28, secured to said sleeve and passing freely through a groove in the collar 23 and the parts secured thereto. The spline 28 is 10 continued above the collar 23 and forms a spring-arm 29, having a shoulder 31 at its upper end, said spring-arm passing through the type-wheel 30, which is mounted on the sleeve 27, and the shoulder 31 at the upper end of 15 the spring-arm serves to retain the type-wheel in place, but permits it to be removed when desired. The lower end of the sleeve 27 is provided with a grooved collar 32, which is engaged by a yoke 33 at one end of an arm 20 34. The other end of the arm 34 is pivotally attached to the machine-frame, and said arm is normally pressed downwardly by a spring 35. Key-levers 36 37, designated for figures and capitals, are pivotally attached to the ma- 25 chine-frame and adapted to raise the pivoted arm 34 different distances (being limited by screws 38 39) for raising the sleeve 27 and the type-wheel mounted for presenting capitals and figures to writing position. From the 30 construction and arrangement of parts above described it will be seen that the type-wheel can be raised without in the least disturbing the gearing which rotates the wheel, and thus friction and wear heretofore encountered by 35 the teeth of the gears sliding on each other when the type-wheel is raised is entirely avoided.

I have hereinbefore referred to the dog 26, engaging the star-wheel 25 to lock the type-wheel after the latter has been positioned for writing. I will now describe in detail the devices which I employ for operating this dog.

A stud 40 projects laterally from a plate 41, secured to the frame of the machine in 50 proximity to the star-wheel 25, and on said stud a sleeve 42 is loosely mounted. An arm 43 projects upwardly from the sleeve 42 and has secured to it a plate 44, provided with a beveled edge 45 and constituting a dog to en- 55 gage the star-wheel, so as to lock the latter and the type-wheel in proper position for writing. Should the movement of the type-wheel when positioned by the key-lever be slightly inaccurate—that is to say, moved a little too far or 60 not quite far enough—the engagement of the beveled edge 44 of the dog 26 will engage the beveled face of one of the teeth of the star-wheel and move the latter to bring the type-wheel connected with it exactly in the proper 65 position to insure the accurate printing of the

type character. An arm 46 projects from the sleeve 42 nearly at right angles to the arm 43 and dog 26, and at the free end of the arm 46 a stud 47 projects outwardly therefrom and carries a roller 48. A segmental cam- 70 plate 49 is pivoted at 50 to the frame of the machine and is provided on its upper edge with a shoulder 51, located some distance from one end, so that when a key-lever is operated the plate will move under the roller 75 48 without operating the dog 26 while the wheel-movers are operating to position the type-wheel, and so that after this shall have been accomplished the shoulder 51 will engage the roller 48 and cause the sleeve 42 to 80 turn and throw the dog into engagement with the star-wheel 25 to lock the type-wheel, as above explained, during which time the cam edge 52 of the cam-plate will ride under the roller 48. While it is true that when the 85 flier strikes the key-lever which has been operated further movement of the type-wheel will be prevented, still the key-lever may be further depressed, and during this continued movement of the key-lever the dog 26 will be 90 operated, the cam-surface of the key-lever being so shaped that after the arms 5 have been properly positioned the remainder of the cam-surface will be concentric with a circle described by the point on the key-lever 95 at that moment in contact with the roller. After the dog 26 has engaged the star-wheel the key-lever cannot be further depressed. In order to insure the continuity of the operation of the wheel-lock devices, some provision should be made to avoid wear of the cam edge 52 of the cam-plate 49, so that said cam edge will always be the same distance from the fulcrum of said plate. To accomplish this, I place on the cam edge 52 a light spring 100 105 53, which is secured at one end thereto and terminates at its other end at the shoulder 51. In order to insure the retention of the segmental cam-plate 49 and the roller 48 of the crank in operative relation to each other, a flat spring 54 may be employed, one end of said spring being secured to a lug 55 on the cam-plate and bearing at its other end upon the roller 48. A frame 56 is also pivotally attached at one end by means of the same 110 pivot-pin, 50, which pivotally supports the cam-plate 49, and the other end of said frame is provided with a screw 57, which enters an elongated slot 58 in the cam-plate, so as to provide means for adjustably connecting the 115 pivoted frame 56 and cam-plate 49 together. Two arms 59 project from the end of the pivoted frame 56, and to the free ends of these arms two rods 60 are loosely connected. The rods 60 depend from and are preferably made 120 integral with a curved bar 61, located upon the key-levers. Thus when a key-lever is depressed the bar 61 will be caused, through the medium of the rods 60, to tilt the pivoted frame 56 and the cam-plate 49, resulting in 130

throwing the dog 26 into engagement with the star-wheel 25 to lock the type-wheel, as hereinbefore explained. When a key-lever is released and the parts return to their normal 5 positions, the spring 54, bearing upon the roller 48 of the crank, will serve to move the dog 26 away from the star-wheel 25.

Various slight changes might be made in the details of construction of my invention 10 without departing from the spirit thereof or limiting its scope, and hence I do not wish to limit myself to the exact details herein set forth.

Having fully described my invention, what 15 I claim as new, and desire to secure by Letters Patent, is—

1. The combination with a type-wheel carrier, of two segmental wheel-movers, a pinion interposed between said movers, gearing connecting said pinion and type-wheel carrier, devices for limiting the forward movement of the wheel-movers, and devices carried by the latter and by the interposed pinion for locking one of said movers against movement 25 when the other is engaged by a key-lever.

2. The combination with a type-wheel carrier, of two wheel-movers each having a forwardly and inwardly projecting arm, a roller carried by each arm, a series of key-levers for 30 each roller and means for positively locking one wheel-mover when the other is engaged by any one of its key-levers.

3. The combination with two wheel-movers each having teeth, and a forwardly and inwardly projecting arm, a pinion interposed 35 between said teeth and carrying a flier, and a set of key-levers for each projecting arm, of devices carried by the wheel-movers and interposed pinion for positively locking one 40 wheel-mover when the projecting arm of the other is engaged by any one of its key-levers.

4. The combination with wheel-movers having teeth and forwardly and inwardly projecting arms, a set of key-levers for each arm 45 and a pinion interposed between the teeth of the two wheel-movers, of a segmental disk carried by the pinion and a pin carried by each wheel-mover, the said disk and pins co-operating to lock one wheel-mover when the 50 arm of the other is engaged by one of its key-levers.

5. The combination with two wheel-movers each having teeth and a forwardly and inwardly projecting arm, a pinion interposed 55 between the teeth of said movers, and carrying a segmental disk and toothed segment and a type-wheel carrier having a pinion engaged by said toothed segment, of a set of key-levers for each wheel-mover and pins carried by the 60 latter and adapted to be engaged by the segmental disk, whereby when one wheel-mover is actuated by a key, the other will be locked by the contact of the segmental disk with the pin.

6. The combination with two wheel-movers

having teeth, a pinion interposed between said teeth and carrying a disk and a flier, and a pin on each wheel-mover, of a series of key-levers for each wheel-mover, each key-lever adapted when actuated to move in the path of 70 the flier and limit its movement.

7. In a type-writing machine, the combination with a post, of a pinion through which said post passes, means for preventing vertical movement of the pinion, a sleeve on the 75 post and movable vertically through the pinion, a type-wheel mounted on the sleeve, a spline secured to the sleeve and passing through a groove in the pinion, said spline terminating in a spring-arm passing through 80 the type-wheel to hold it in place, a grooved collar at the lower end of said sleeve and devices engaging said grooved collar for raising the sleeve and type-wheel carried thereby.

8. In a type-writing machine, the combination with a type-wheel and a star-wheel connected therewith, of a dog for engaging the star-wheel to lock the type-wheel, a cam-plate for operating the dog, key-levers, devices actuated by the key-levers for operating the 90 type-wheel, and connections between the key-levers and said cam-plate for transmitting motion to the latter to throw the dog after the type-wheel has been moved.

9. In a type-writing machine, the combination with a type-wheel and a star-wheel connected therewith, of a dog to engage the star-wheel, a crank connected with said dog, a cam-plate for operating said crank, a key-lever and operating devices between the key- 100 lever and cam-plate.

10. In a type-writing machine, the combination with a type-wheel, and a star-wheel connected therewith, of a dog to engage the star-wheel, a crank connected with said dog, 105 a cam-plate engaging the crank, a spring carried by the cam-plate and engaging the crank, a key-lever and operating devices between the key-lever and the cam-plate.

11. In a type-writing machine, the combination with a type-wheel, and a star-wheel connected therewith, of a pivoted dog, a crank connected with said dog, a cam-plate for engaging the crank to throw the dog into engagement with the star-wheel, a pivoted 110 frame, a connection between the cam-plate and pivoted frame, a key-lever, and operating devices between the key-lever and pivoted frame.

12. In a type-writing machine, the combination with a type-wheel and a star-wheel connected therewith, of a dog to engage the star-wheel; a cam-plate for operating the dog, a key-lever, operating devices between the key-lever and cam-plate and means for accomplishing the adjustment of said operating devices.

13. In a type-writing machine, the combination with a type-wheel and a star-wheel connected therewith, of a dog to engage the 115

star-wheel, a crank carried by the dog, a cam-plate to engage the crank, a pivoted frame adjustably connected with said cam-plate, key-levers, and connections between said key-levers and pivoted frame.

14. In a type-writing machine, the combination with a type-wheel and a star-wheel connected therewith, of a dog to engage the star-wheel, a crank connected with said dog, a cam-plate having a cam edge, a shoulder on said cam edge, a spring on the upper portion

of the cam edge of the plate to prevent wear of the same, one end of said spring terminating in proximity to said shoulder, and means for operating the cam-plate.

In testimony whereof I have signed this specification in the presence of two subscribing witnesses.

JOHN GEORGE NIEDERER.
